UNITED STATES PATENT OFFICE.

GIANNI CAPRONI, OF MILAN, ITALY.

COOLING SYSTEM.

Application filed October 1, 1920. Serial No. 414,019.

To all whom it may concern:

Be it known that I, GIANNI CAPRONI, a subject of the King of Italy, residing at Milan, Italy, have invented certain new and useful Improvements in Cooling Systems, of which the following is a specification, reference being had therein to the accompanying drawing.

This invention is a novel cooling system or method and apparatus for lowering the temperature of the atmosphere, for example, in living rooms, railway cars, or the like. The general object of the present invention is to afford a cooling system and apparatus which will be simple and inexpensive of construction as compared with heretofore known air cooling systems, and easy and convenient of operation and control. A further object is to afford for these purposes an apparatus of small size and readily portable in nature, so that it can be shifted from room to room as desired. Further objects and advantages of the present invention will be elucidated in the hereinafter following description of one form or embodiment thereof or will be apparent to those conversant with the subject.

To the attainment of the objects and advantages above referred to, the present invention consists in the novel cooling system or method and apparatus herein illustrated and described, and the novel features of combination, arrangement and structure therein contained.

In the accompanying drawings, Figure 1 is a rear elevation, partly in section, of a cooling apparatus embodying the principles of the present invention.

Figure 2 is a side elevation, partly in section, of the same.

Figure 3 is an enlarged central section of the air escape device at the front of the apparatus.

Figure 4 is a cross-section taken on the plane 4-4 of Figure 3; and

Figure 5 is a front view of the parts shown in Figures 3 and 4.

The illustrated structure and details may be specifically described as follows. The portable apparatus is shown as having a suitable flange or base 10 adapted to rest upon the floor. This base is formed at the bottom of a casing or vessel 11 within which the cooling of the air is performed, or the exchange of heat between the air and the cooling water. The top of the cooling ves-

sel 11 is closed by flanged cover 12. Above the cover are shown extending upwardly a pair of opposite standards 13, which, by means of bearings or trunnions 14, give support to a motor casing 15 and the parts carried thereby. The apparatus is preferably electrically driven, wherefore the casing 15 will contain an electric motor, the details of which form no part of the invention but will be understood. At the rear side of the casing 15 is the main casting or support 16 of the air compressor, the cylinder 17 of which is mounted directly above 16. The above mentioned parts and their contained or attached parts substantially constitute the entire apparatus of this invention, which is thus seen to be self-contained and portable.

Ordinary cold water from a hydrant or other source is the illustrated means of extracting and conveying away the heat of the air under treatment. In the case of railway cars, the heated water might be cooled by any well known exterior radiator or cooler, and recirculated. For convenience, however, I have shown merely a water supply 20 in the nature of a cold water pipe or hydrant. If necessary a motor driven pump 21 can be connected so as to give greater circulating force to the water. A connecting pipe 22 extends to the inlet 23 at the upper side of the cooling vessel 11. The pipe 23 does not lead directly into the body of water in the vessel but connects with a downwardly extending central tube 24 so that the incoming water is directed and spread at the bottom of the vessel. The vessel is shown as having a non-conducting lining 25 which tends to prevent the interior operations being affected by exterior temperatures.

The cool water at the bottom of the vessel rises gradually and passes out at the top through an exit pipe 26 from which leads a connection or tube 27. Instead of wasting the heat contained in the outgoing water, the same may be conducted to a tank 28 and thence tapped by a hydrant 29. In this way the apparatus hereof is utilized not only for cooling the atmosphere but for furnishing warm or hot water for hydrant purposes.

The driving motor shaft 33 has at its rearward end a crank 34 which connects by a pitman 35 with the reciprocating piston 36 within the compressor cylinder 17. The complete details of an air compressor need

not be here shown, as this subject is well understood to those skilled in the art of air compression. The clearance space should be minimized and efficient valves employed so 5 as to insure the maximum delivery of compressed air at each stroke.

For example, a valve 37 may be provided in the head of the piston 36, and a second valve 38 may be provided in the hollow 10 tension 39 of the compressor cylinder. In this way each rotation of the motor delivers air under considerable pressure into the connecting pipe 40 which leads from the valve 38.

15 As is well understood, this compression of the atmospheric air effects a concentration of heat and thereby an extensive elevation of temperature. By now extracting heat through cooling water so as to bring the 20 compressed air to normal temperatures, we are enabled to effect the desired heat removal and subsequently, upon the release and expansion of the air, the resultant drop in temperature will bring about the desired 25 cooling effect in the surrounding atmosphere.

The compressed air pipe 40 leads to the inlet connection 41 by which the air passes into the cooling vessel 11. Within the cooling 30 vessel the air passes through air coils 42. These, for example, may be copper tubes so arranged that the traveling hot air progressively descends through the depth of the cooling vessel while its contact with the coil 35 tubes, themselves contacting the cooling water at the outside, causes a progressive exchange of heat, the heat passing to the water, and the air eventually coming out of the coils by the pipe 43 at substantially normal 40 temperatures. The pipe 43 is shown as passing up through the descending water conduit 24 and passing through a special packed connection at the top thereof. The air pipe is continued at 44 above the cooling 45 vessel and conducted to the escape valve about to be described.

The escape valve 45 may be of various forms but is preferably one which gives intermittent discharges of air of predetermined quantity, this being more regular and durable and less noisy than a needle valve. The motor casing 15 is formed with a fixed axial sleeve 46. Inside of this rotates an internal sleeve 47 formed or secured on the 50 motor shaft 33. The internal sleeve is formed with an interior chamber 48, this chamber receiving compressed air at each operation and subsequently releasing it, thus constituting an operative escape device. The 55 motor connection 44 conducts the air to a port 49 in the exterior sleeve 46. A port 50 is formed in the interior sleeve 47 and periodically comes opposite the port 49 so as to admit compressed air to the chamber. As 60 the port 50 comes around to the opposite

or upper side, it comes to the port or groove 51 formed in the sleeve 46 and leading forwardly into the atmosphere. The forward end of sleeve 46 is shown as provided with a flared exit or flange, and the escaping air 70 passes from this directly into the atmosphere of the room. Each delivered and expanded portion of air thus brings down to that extent the temperature of the surrounding atmosphere. 75

After the apparatus has been well started it will be seen that a uniform quantity of air will be discharged into the room at each shaft rotation. The air pump or compressor being positive is substantially constant in action, and the interior air pressure will therefore quickly adjust itself so that the quantity of air received and delivered through the escape chamber 48 at each operation will balance or equal the amount of air forced into the system at each stroke. Obviously, if the chamber 48 be enlarged it will receive a greater quantity of compressed air, with the result that the internal air pressure will automatically decrease so 85 that the total quantity of air discharged at each operation will be restored to the original uniform amount. Utilizing this principle, I afford a means of controlling the pressure of the internal air and, by controlling its pressure, regulating its temperature and thereby regulating the cooling 90 effect. 95

A regulator 55 is shown in the form of a cylindrical plug which extends partly within the chamber 48. This is provided with a screw-threaded portion 56 engaging within the fixed sleeve 46. The forward end of the regulator is squared at 57 to permit turning by a wrench. Assume now the regulator to be adjusted to reduce the chamber 48. The chamber will then be able to receive and deliver less air on each rotation. The result will be that air will accumulate in the interior, thus giving an increase of pressure and a corresponding internal temperature. The cooling water flowing through the vessel 11 will therefore be able to more effectively extract heat from the air under treatment. When the increase of pressure arrives at the point where the reduced chamber 48 can receive and deliver the normal quantity of air, uniformity will again be restored. The described regulation gives a greater cooling effect. The greater interior pressure calls upon the motor for greater service, and with the higher internal temperature a greater quantity of the cooling water can be utilized. 110 115 120 125

When a water pump is used, as diagrammatically shown at 21 in Fig. 1, it will preferably be driven by the same motor as the compressor and escape device, and for this purpose will be mounted on the casing 15 or 16. 130

The fulcra 14 permit the casing 15 to be swung so that the air outflow may be directed horizontally, upwardly, or downwardly at will.

5 It will thus be seen that I have described an air cooling apparatus, and a system or method carried out therein, accomplishing the purposes and embodying the principles of the present invention. Since various 10 matters of method, combination, design and detail may be modified without departing from the underlying principles, it is not intended to limit the invention to such matters except so far as is specified in the appended claims.

What is claimed is:

1. A portable air-cooling apparatus for apartments and the like comprising a frame supporting a cooling vessel, a compressor 20 and a motor, with an air escape device adapted freely to discharge successive portions of air without relieving the air pressure in said vessel, said motor connected to actuate the compressor and the escape device, said compressor connected to deliver

to the cooling vessel, and a gaseous air connection from said vessel to the escape device; together with a hollow base containing the cooling vessel, an upstanding extension of said base, and means pivoting the combined motor, compressor and escape device to said extension. 30

2. A portable air-cooling apparatus for apartments and the like comprising a frame supporting a cooling vessel, a compressor 35 and a motor, with an air escape device adapted freely to discharge successive portions of air without relieving the air pressure in said vessel, said motor connected to actuate the compressor and the escape device, said compressor connected to deliver to the cooling vessel, and a gaseous air connection from said vessel to the escape device; the escape device being swivelled so as to direct its intermittent puffs of cold air in 40 varying directions. 45

In testimony whereof, I have affixed my signature hereto.

GIANNI CAPRONI
